PORTABLE INHALATOR CABINET

John Charles Hallisey, Chicago, Ill.

Application March 2, 1949, Serial No. 1,165

Term of patent 14 years

(Cl. D14—3)

To all whom it may concern:

Be it known that I, John Charles Hallisey, a citizen of the United States, residing at Chicago, in the county of Cook and State of Illinois, have invented a new, original, and ornamental Design for Portable Inhalator Cabinet, of which the following is a specification, reference being had to the accompanying drawing, forming part thereof in which:

Fig. 1 is a front perspective view of a portable inhalator cabinet showing my new design as it appears when the top is open; and

Fig. 2 is a rear perspective view of the portable inhalator cabinet with the top shown closed.

I claim:

The ornamental design for a portable inhalator cabinet, substantially as shown.

JOHN CHARLES HALLISEY.
